DESIGN.

L. LAPIDUS.

COMBINED HINGE AND BRACKET SOCKET PIECE FOR LAMP CASINGS.

APPLICATION FILED JAN. 5, 1921.

59,498.

Patented Oct. 25, 1921.

Inventor:

Leon Lapidus,
By his Attorney, Geo. W. Mather

UNITED STATES PATENT OFFICE.

LEON LAPIDUS, OF BROOKLYN, NEW YORK.

DESIGN FOR A COMBINED HINGE AND BRACKET SOCKET-PIECE FOR LAMP-CASINGS.

59,498.

Specification for Design.

Patented Oct. 25, 1921.

Application filed January 5, 1921. Serial No. 435,277. Term of patent 3½ years.

To all whom it may concern:

Be it known that I, LEON LAPIDUS, a citizen of the United States, residing in the borough of Brooklyn, county of Kings, city and State of New York, have invented a new, original, and ornamental Design for a Combined Hinge and Bracket Socket-Piece for Lamp-Casings, of which the following is a specification, reference being had to the accompanying drawing, forming part thereof.

The figure is a perspective view of a combined hinge and bracket socket piece for lamp casings, showing my new design.

I claim:

The ornamental design for a combined hinge and bracket socket piece for lamp casings, as shown.

LEON LAPIDUS.
